UNITED STATES PATENT OFFICE

WILLIAM WALLACE, OF LA FAYETTE, INDIANA

BASKET BALL BANK BOARD SUSPENSION

Application filed April 13, 1931. Serial No. 529,738.

This invention relates to the art of suspending basket ball basket boards over a court from overhead members.

A primary object of the invention is to provide a basket board suspension which will permit the board to be raised and lowered as may be desired to remove it from the playing position over the court and at the same time provide means for retaining the board in a vertical position when the board is dropped to the playing position.

An important object of the invention is to provide means for retaining the board in a rigid position at the lower end of the board carrying members whereby diagonal braces between the board and the members may be avoided.

A further important object of the invention resides in the means for easily and quickly adjusting the angle of the board about the lower end of a supporting member.

These and other objects will become apparent in the following description of the invention as illustrated in the accompanying drawings, in which

Fig. 1 is a side elevation of a basket ball basket board embodying my invention;

Fig. 2, a fragmentary front elevation of the basket board;

Fig. 3, a detail in fragmentary side elevation of the board adjusting mechanism; and

Fig. 4, a detail in horizontal section on the line 4—4 in Fig. 3.

Like characters of reference indicate like parts throughout the several views.

Pivoted to a suitable overhead support such as the member 10 are a pair of tubular members 11 and 12 the lower ends of which are rigidly united by the spacing tube 13. This tube preferably extends laterally through the ends of the members 11 and 12 and is welded thereto on the inner sides of the members. The tubular members 11 and 12 may be raised and lowered as a unit by means of the hoisting mechanism 14 and cable 15.

A rod 16 is slidably passed through the tubular tie member 13 to project beyond each of the side members 11 and 12 a slight distance. Arms 17 and 18 are welded to ends of

50 the spacing member 13 which project out-

wardly from beyond the members 11 and 12. These arms 17 and 18 are angularly positioned in relation to the members 11 and 12 so that when the members 11 and 12 are dropped downwardly to a playing position, these arms 55 are then in substantially vertical and parallel positions.

The bank board 19 is provided with the vertical angle bars 20 and 21 at each end and on its rear side respectively. The rearwardly disposed legs of these bars 20 and 21 are centrally bored therethrough to rockably receive the ends of the rod 16 so as to support the board 19 thereby. From the upper side of the board 19 extend cables 22 and 22' to the overhead support, which cables serve to limit the downward swing of the members 11 and 12 and the board 19 thereon.

The upper and lower ends of each of the arms 17 and 18 are provided with inturned ears 23 and 24 respectively through which are screw-threadedly passed adjusting screws 25 and 26 respectively. Lock nuts 27 are carried on these screws back of the ears. By

70 suitably adjusting the screws 25 and 26 forwardly and rearwardly through the ears of the arms so as to have the forward ends of the screws contact with the laterally disposed legs of the angle bars 20 and 21, the board 19 may be rockably adjusted about the rod 16 so as to position and there retain the board 19 in a vertical position. By means of the screws 25 and 26 extending from the fixed arms 17 and 18 against the rockable board 19, the board is held rigidly with respect to the side members 11 and 12 so that

75 although the board may be struck with considerable force by a ball during play, the board will remain rigidly disposed and will not vibrate.

90 It is also to be seen that by means of the above described structure, the board 19 may be rigidly positioned about the ends of the rigid members 11 and 12 without there having to be diagonally disposed brace members between the board 19 and the members 11 and 12 as has heretofore been the practice so that there is no interference from such heretofore employed braces and the board may 95 100

be readily adjusted without there having to be a matching of bolt holes or the like.

While I have here shown and described my invention in the one form as now best known to me, it is entirely obvious that structural changes may be made without departing from the spirit of the invention and I therefore do not desire to be limited to that precise form nor any more than may be required by the following claims.

I claim:

1. In combination with a pair of rigid members, a tie bar interconnecting the lower ends of the members, an arm fixed at the lower end of each of the members, ears at top and bottom of each arm, a basket board pivotally supported about the lower ends of the said members, and adjusting screws through said ears adapted to abut said board and retain said board at selective angles about said members.

2. A pair of rigid support members, a basket board rockably carried at the ends of the members, arm fixed in relation to the members, and plural means one above and one below the rockable connection and between the arms and the board for retaining the board at selective positions of rotation.

3. A pair of rigid members pivotally carried by their upper ends by an overhead support, a basket board rockably carried on the lower ends of the members, a cable between the board and the overhead support limiting the downward swing of said members, and screw means for adjusting and retaining said board in selective positions of rotation about the members.

4. In a basket board support, a pair of rigid members, a basket board, trunnions carried by the members, bars on the board extending rearwardly to be rockably carried by the trunnions, arms carried by the members in fixed positions extending below and above said trunnions, and screws between the upper and lower ends of the arms and the board.

5. A pair of rigid members, a tubular member interconnecting lower ends of the members, a bar through the tubular member projecting beyond said rigid members, an arm fixed at the side of each rigid member extending above and below said bar, a basket board, supporting bars extending rearwardly of the board and rockably carried on the ends of said tubular member bar, said board being carried by said supporting bars to extend above and below said member bar, and adjusting members between the arms and the board.

In testimony whereof I affix my signature
WILLIAM WALLACE.
